UNITED STATES PATENT OFFICE

EDWARD B. ALLEN, OF NEWTOWN, CONNECTICUT, ASSIGNOR TO THE SINGER MANUFACTURING COMPANY, OF ELIZABETH, NEW JERSEY, A CORPORATION OF NEW JERSEY

THREAD CUTTING MECHANISM

Application filed March 3, 1928. Serial No. 258,772.

This invention relates to thread-cutting mechanism for sewing machines, more particularly of the buttonhole type, and has for an object to improve the thread-cutting mechanism disclosed in the patents to Allen No. 1,579,200, of April 6, 1926, and No. 1,600,206, of September 21, 1926, to secure a uniformly high degree of certainty of operation of the mechanism in sewing operations on all of the 10 various classes of material met with in practice. Buttonhole sewing machines are commonly called upon to sew buttonholes in fabrics of widely different physical characteristics, some of such fabrics being knitted and 15 others being woven; both knitted and woven fabrics varying greatly in thickness, weight, texture, etc.

In my prior thread-cutting mechanism there is embodied a scissors thread-cutter, 20 the blades of which are disposed transverse to the plane of the work. Such thread-cutter is carried by a swinging lever which moves it in an arcuate path causing one of the blades to graze the under surface of the work and 25 pass between the latter and the sewing threads and cord which lie parallel to and in contact with the under surface of the work from the last stitch to the needle-throat member, from which they are drawn out by the 30 movement of the work-clamp from sewing position to buttonhole cutting position at the end of the sewing period.

The setting or adjustment of the operative radius of such thread-cutter is rather critical as, if too short, the upper scissors point is 35 not likely to catch all of the threads and cord and, if too long, there is danger that the scissors point will snag the work, particularly if the latter is of a soft or spongy 40 nature allowing the threads to sink into the fabric.

According to the present improvement, provision is made for relatively separating the work and threads to be cut, to provide a space 45 for entry of the thread-cutter or scissors point, thus materially broadening the range of allowable variation in the adjustment and maintenance of the operative path or radius of the thread-cutter, for successful operation.

While various specific mechanisms may ob-

viously be provided for relatively separating the work and threads to be cut, it is preferred to accomplish the result by lifting and holding lifted the front end of the work-clamp, and such lifting may be conveniently effected by a cam fixed to the thread-cutter 55 carrying lever.

In the accompanying drawings Fig. 1 is a side elevation of a buttonhole sewing machine embodying the invention. Fig. 2 is a 60 front end elevation of the machine. Fig. 3 is a rear view and Fig. 4 an end view of the work-clamp lifting cam and associated parts. Fig. 5 is a plan view of the parts below the work-clamp of the machine. Fig. 6 is a section on the line 6—6, Fig. 1. Fig. 7 is a section on the line 7—7, Fig. 6. Fig. 8 is a side elevation of the work-clamp and thread-cutter in thread-cutting position. Fig. 9 is a perspective view of the clamp-lifting cam-follower, and Fig. 10 is a transverse sectional view through the work-clamp showing the 65 thread-cutter in cutting position.

In the preferred embodiment of the invention illustrated, 1 represents the bed, 2 the standard, 3 the overhanging arm and 4 the head of a buttonhole sewing machine of the type disclosed in the patent to Allen No. 1,532,400, reissued April 4, 1922. The stitch-forming mechanism is constructed substantially in accordance with the disclosure of the Allen et al. Patent No. 1,372,473, of 70 March 22, 1921, and comprises the reciprocating and laterally vibrating needle 5 and the usual underthread mechanism mounted 75 on the rotary turret 6 and including the threaded looper 7, non-threaded looper 8 and loop-detainers 9 and 10. The turret 6 also carries the needle-throat member 11 which is formed with the usual needle-aperture 12 and 80 guideway for the stay-cord c. The period of 85 operation of the stitch-forming mechanism is controlled by the usual stop-motion device 13 by which the flow of power from the continuously running belt-pulley 14 to the sewing shaft 15 is established and interrupted.

The buttonhole cutting mechanism is constructed substantially in accordance with the disclosure of my said reissued patent and 90 comprises the upper and lower cutter-levers 100

16, 17 which are fulcrumed at 18 on the travelling fulcrum-block 19 which carries the cutter-levers forwardly from the retracted position, shown in full lines in Fig. 8, to buttonhole cutting position in register with the stitched buttonhole shown in such figure. The cutter-levers and fulcrum-block derive their operative movements from the usual cutter-advancing and -retracting cam 20 and cutter-closing cams 21, 22 on the cutter-shaft 23 which is actuated through a suitable clutch-connection from a constantly running belt-pulley, not shown.

The work-clamp, except as hereinafter noted, is of the usual construction disclosed in said reissued patent. It comprises the lower work-supporting plates 24 and upper clamping feet 25 carried by the clamp-arms 26 fulcrumed at 27 on the blocks 28 mounted on the plates 24. The clamp-plates 24 are carried by the usual cross-slide-plate 29 which, in turn, is carried by the usual longitudinal slide-frame 30. The cross-slide-plate 29 and longitudinal slide-frame 30 have the usual operative connections with the feed-wheel 31, which is given a step-by-step feeding movement through the usual connections with the sewing shaft 15, to place the stitches around the buttonhole. It is also given a rapid continuous movement, both prior and subsequent to sewing, by the rapid-feed shaft 32 through the gear-connection 33 with the cross-shaft 34 operated at the proper times by a clutch-connection, not shown, with the gear 35 driven continuously by the worm 36 on the rapid-feed shaft 32. During the rapid continuous movement of the feed-wheel 31, the work-clamp is shifted forwardly, transversely of the needle-path from buttonhole-cutting position, Fig. 8, to stitching position, and, when the sewing is completed, is rapidly returned to buttonhole-cutting position.

It is well known that the needle-throat member of a machine of the type under consideration supports the portion of the work immediately adjacent the sewing point and is adapted to guide a stay-cord to the stitch-forming mechanism, so that the stitches will be formed over the stay-cord and bind the latter in position around the buttonhole. Also, it is known that when the stitch-forming mechanism of a machine of the type under consideration is stopped, a loop of needle-thread is retained by the loop-taker mechanism. Consequently, when the work is shifted rearwardly from sewing to cutting position, there are four thread-lengths leading from the needle-throat member to the last stitch. One of these threads is the stay-cord. Another is the under or looper-thread. The remaining two are the limbs of the detained needle-loop. These threads lie substantially parallel to and in contact with the under surface of the work.

65 The work-clamp is closed by a rocking

movement of the connected rock-shaft sections 38 one of which has fixed thereto the rearwardly extending arm 39 which is depressed by the automatically operated lever 40, the action of which is described in said reissued patent. The rock-shaft sections 38 may be manually operated to close the work-clamp by rearward motion of the usual upwardly extending finger-piece 39' fixed to the same rock-shaft section 38 which carries the rearwardly extending arm 39. The clamp-closing means may thus be either manually or automatically operated.

The thread-cutter is constructed substantially in accordance with the disclosure of the patent to Allen No. 1,579,200 of April 6, 1926. It comprises a scissors device having an upper pointed blade 41 fixed to and carried by the thread-cutter lever 42 which is fulcrumed at 43 to the machine frame. Pivoted at 44 to the upper scissors-blade 41 is the lower scissors-blade 45 the tail of which has a lateral projection 46 entering the scissors-closing cam-slot 47 in the stationary cam-plate 48. This scissors device is disposed in a vertical plane $\alpha-\gamma$ transverse to and intersecting the lead of the threads and cord extending from the needle-throat member to the stitched buttonhole, when the latter has been shifted to buttonhole cutting position, Fig. 8.

The thread-cutter lever 42 is operated by a link-connection 49 with a lever 50 fulcrumed at 51 to the frame-bracket 52 and having a follower 53 entering the thread-cutter cam-groove 54 in the gear 33, as disclosed in the patent to Allen No. 1,600,206, of September 21, 1926.

In my prior constructions the scissors device was preferably adjusted to an operative radius such that the upper pointed blade grazed the under surface of the work and entered between the latter and the threads to be cut. According to the present improvement, means are provided for relatively separating the under surface of the work and the threads and cord, to provide a space for entry of the upper scissors-blade, thus materially broadening the range of allowable variation in the adjustment and maintenance of the operative path or radius of the thread-cutter. The separation of the work and threads to be cut is preferably effected by relatively moving the work-clamp and needle-throat member vertically. In the present machine this relative movement is effected by lifting the work-clamp; such lifting being effected by means carried by the thread-cutter lever 42 and adapted to elevate the front end of the work-clamp during the advance of the thread-cutter to operative position.

The lower clamp-plates 24 have at their rearward ends the usual laterally slidable connection 55 with the under-cut forward edge of the retainer-plate 56 fixed to the cross-slide-plate 29, as disclosed in said reissued

patent. This connection is free enough to permit of the upward tilting of the work-clamp sections about such connection as a center. Connected to sockets in the front ends of the work-clamp sections are the ball-shaped upper ends 57 of pins 58 which are received in the tubes 59 fixed to the plate 60 carrying the cam-follower roll 61. The pins 58 are grooved at 62 for reception of the circular portion 63 of the latch-lever 64 which is fulcrumed at 65 to the plate 60. The circular portion 63 of the latch-lever is formed at diametrically opposed points with recesses 66 which, when shifted into register with the pins 58, permit upward removal of such pins from the tubes 59 in removing the clamp-sections from the machine. The spring 67 biases the latch-lever 64 to locking position, Fig. 7. The tubes 59 are slidably received in holes 68 in the block 69 secured to the cross-slide-plate 29. The spring 70 yieldingly retains the clamp-plates 24 upon the cross-slide-plate 29. The stop 69' limits the downward motion of the plate 60 under the influence of the spring 70 when the pins 58 are released. Screwed into the thread-cutter lever 42 are the stud-pins 71 to the outer ends of which is fixed the cam-plate 72 having a portion 73 concentric with the pivotal center 43 of the lever 42 and a portion 74 extending nearer the center 43 from the portion 73.

When the work-clamp is shifted to button-hole cutting position, Fig. 8, the follower roll 61 lies directly over the cam-plate 72 so that, as the thread-cutter lever 42 is operated to advance the thread-cutter, the pins 58 are lifted, thus tilting the work-clamp upwardly and raising the stitched work relative to the needle-throat member 11, as shown in Fig. 8. This action separates the under surface of the work from the threads extending from the last stitch to the needle-throat member, and causes such threads to extend at an angle to the under surface of the work, the space within such angle being ample to receive the pointed upper blade of the thread-cutter which need not be set or adjusted as finely as would be necessary were no preliminary separation of the work and threads, provided for. The point 41' of the upper scissors-blade is preferably offset or curved forwardly toward the needle-throat member from the thread-cutting plane, $x-y$, to take advantage of the increased space provided for entry of such point between the work and the threads, at the increased distance from the apex of the angle formed by the under surface of the work and threads to be cut.

The thread-cutter carries a nipper 75 for seizing the severed needle-thread loop 76 and removing it from the stitch-forming mechanism. This nipper is constructed substantially in accordance with the disclosure of said Patent No. 1,579,200.

Having thus set forth the nature of the invention, what I claim herein is:

1. In a sewing machine in which the thread to be cut extends from the last stitch to the needle-throat member substantially in contact with the under surface of the work, a thread-cutter including an element normally occupying a retracted position, means for relatively separating the work and threads to be cut to provide a space for entry of the thread-cutter element, and means for projecting the thread-cutter element into such space. 70

2. A sewing machine including stitch-forming mechanism, a needle-throat member, a work-clamp, means for relatively feeding the stitch-forming mechanism and work-clamp to sew a group of stitches and for relatively shifting the stitch-forming mechanism and work-clamp after the sewing is completed to laterally space the group of stitches from the needle-throat member, a thread-cutter including a pointed blade disposed transverse to the plane of the work and below the work-clamp, means for relatively separating the work and the threads leading from the needle-throat member to the group of stitches to provide a space for entry of the thread-cutter blade, and means for projecting the point of the thread-cutter blade into such space to sever the threads. 85

3. In a sewing machine in which that portion of the thread to be cut lies substantially in contact with the surface of the work, a thread-cutter including a blade disposed transverse to the surface of the work and having a pointed extremity, means for relatively separating the work and that portion of the thread to be cut to provide a space for entry of the point of the thread-cutter blade, and means for projecting the thread-cutter blade into such space to cut the thread. 100

4. In a sewing machine in which that portion of the thread to be cut lies substantially in contact with the surface of the work, a thread-cutter including a blade having a pointed extremity, said thread-cutter being pivotally mounted so as to direct the movement of the pointed extremity of the blade in a curved path crosswise of the lead of the thread, and means for relatively separating the work and thread to be cut to provide a space for entry of the point of the thread-cutter blade. 110

5. In a sewing machine, stitch-forming mechanism, a needle-throat member, a work-clamp, clamp-closing means, means for relatively feeding the stitch-forming mechanism and work-clamp to sew a group of stitches, means for relatively separating the work-clamp and needle-throat member transversely of the plane of the work while the work-clamp remains closed upon the work, and means for severing the thread while the needle-throat member and work-clamp are relatively separated. 120

6. In a sewing machine, stitch-forming mechanism, a needle-throat member, a work-clamp, clamp-closing means, means for relatively feeding the stitch-forming mechanism and work-clamp to sew a group of stitches and for relatively separating the stitch-forming mechanism and work-clamp transversely of the needle-path after the sewing is completed, means for relatively separating the work-clamp and needle-throat member transversely of the plane of the work, while the work-clamp is closed upon the work, and means for severing the thread below the work while the needle-throat member and work-clamp are relatively separated. 70
- 5 7. In a sewing machine, stitch-forming mechanism, a needle-throat member, a work-clamp, clamp-closing means, means for relatively feeding the stitch-forming mechanism and work-clamp to sew a group of stitches and for relatively separating the stitch-forming mechanism and work-clamp transversely of the needle-path after the sewing is completed, means for lifting the work-clamp 80
- 10 20 while the latter remains closed upon the work, and means for severing the thread while the work-clamp is lifted. 85
- 25 8. In a sewing machine, stitch-forming mechanism, a needle-throat member, a work-clamp, means for relatively feeding the stitch-forming mechanism and work-clamp to sew a group of stitches and for relatively separating the stitch-forming mechanism and work-clamp transversely of the needle-path 90
- 30 35 after the sewing is completed, means for lifting one end of the work-clamp to tilt the latter upwardly, and means for severing the thread while the work-clamp is tilted. 95
- 35 9. In a sewing machine, stitch-forming mechanism, a needle-throat member, a work-clamp, clamp-closing means, means for relatively feeding the stitch-forming mechanism and work-clamp to sew a group of stitches and for relatively separating the stitch-forming mechanism and work-clamp transversely of the needle-path after the sewing is completed, thread-cutting mechanism below the work-clamp, and means operated by the thread-cutting mechanism for relatively separating the work-clamp and needle-throat member vertically while the work-clamp remains closed upon the work. 100
- 40 45 50 110
- 55 10. In a sewing machine, stitch-forming mechanism, a needle-throat member, a work-clamp, means for relatively feeding the stitch-forming mechanism and work-clamp to sew a group of stitches and for relatively separating the stitch-forming mechanism and work-clamp transversely of the needle-path after the sewing is completed, thread-cutting mechanism including a thread-cutter lever mounted below the work-clamp, and means connected to be operated by said lever for lifting the front end of the work-clamp. 115
- 60 65 120
- 65 11. In a sewing machine, stitch-forming mechanism, a needle-throat member, a work-clamp, clamp-closing means, a thread-cutter, and means for relatively separating the closed work-clamp and needle-throat member transversely of the plane of the work and for operating the thread-cutter while the work-clamp is lifted. 125
- 110 125 130

needle-throat member are relatively separated.

17. In a buttonhole sewing machine, stitch-forming mechanism, a work-clamp, a button-hole cutter adapted to cut the buttonhole in a position removed from the stitch-forming mechanism, means for shifting the work-clamp from stitching position to buttonhole cutting position, a thread- and cord-cutter below the work-clamp, and means for lifting the work-clamp in buttonhole cutting position for the operation of the thread- and cord-cutter.

18. In a sewing machine, stitch-forming mechanism including a needle, a needle-throat member, a work-clamp occupying a position spaced laterally of the needle-path from the needle-throat member at the end of a sewing operation, whereby the thread to be cut extends from the last stitch to the needle-throat member substantially in contact with the under surface of the work, means for relatively separating the work-clamp and needle-throat member to cause the thread leading to the last stitch to stand at an angle to the under surface of the work, a thread-cutter having a blade operating in a path transverse to the lead of the thread and close to the last stitch, said blade having a pointed extremity spaced further than the blade prop- ed from the apex of the angle between the work and thread.

19. In a sewing machine, stitch-forming mechanism including a needle, a work-clamp, clamp-closing means, a needle-throat member, means for relatively separating the needle-throat member and closed work-clamp transversely of the plane of the work to draw out a length of thread from the needle-throat member and separate such thread from the under surface of the work preparatory to a thread-severing operation, and means for entering the space between the separated thread and work and for severing such thread.

45 20. In a sewing machine, stitch-forming mechanism including a needle, a work-clamp, clamp-closing means, a needle-throat member, means for relatively separating the needle-throat member and closed work-clamp in di- rections laterally of the needle and transverse- ly of the plane of the work to draw out a length of thread from the needle-throat mem- ber and separate such thread from the under surface of the work preparatory to a thread- severing operation, and means for severing such thread while it is separated from the work.

In testimony whereof, I have signed my name to this specification.

EDWARD B. ALLEN.

CERTIFICATE OF CORRECTION.

Patent No. 1,867,129.

July 12, 1932.

EDWARD B. ALLEN.

It is hereby certified that error appears in the printed specification of the above numbered patent requiring correction as follows: Page 3, line 53, for the term "x'-y" read x-y; page 4, line 102, claim 14, for "worn-clamp" read work-clamp; page 5, line 37, claim 19, after "work-clamp" insert the words in directions laterally of the needle and; and that the said Letters Patent should be read with these corrections therein that the same may conform to the record of the case in the Patent Office.

Signed and sealed this 25th day of October, A. D. 1932.

(Seal)

**M. J. Moore,
Acting Commissioner of Patents.**
